STENOGRAPHER'S NOTEBOOK COVER AND HOLDER

John H. Becker, St. Louis, Mo., assignor to E. K. Davis, St. Louis, Mo.

Application December 27, 1937, Serial No. 181,795

1 Claim. (Cl. 281—33)

My invention has relation to improvements in notebook holders and it consists in the novel features of construction more fully set forth in the specification and pointed out in the claim.

5 The invention is primarily adapted to serve as a cover and holder for stenographers' notebooks so that the notebook may be enclosed within the covers when not in use, and supported by the covers in an upright position to facilitate transcribing of the notes on the typewriter.

10 My improved cover and holder has for its principal object removable support of the notebook and the erection of the cover of the holder into a rigid supporting stand.

15 It is the further object of the invention to provide a notebook holder that is simple in construction durable, and that may, at the same time, be manufactured at low cost.

20 These advantages, together with others inherent in the invention, will be better apparent from a detailed description of the same in connection with the accompanying drawing, in which:

25 Figure 1 is a plan view of the front cover of the holder containing the notebook, part of the cover being broken away to show the notebook thereunder; Fig. 2 is a plan view of the back cover of the holder; Fig. 3 is a side elevation of the holder containing the notebook; Fig. 4 is a plan view of the holder in open position looking 30 at the face of the notebook supported therein, one corner of which is broken away; Fig. 5 is a side elevation of the holder in erected position showing the notebook supported thereon.

35 Figure 6 is a plan view of the holder opened out flat with the notebook removed and parts of the facing sheets on the inner surfaces of the covers broken away; and Fig. 7 is an enlarged cross-sectional detail taken on the line 7—7 of Fig. 6.

40 Referring to the drawing, N represents a stenographer's notebook of well-known construction having the leaves 1, 1, etc., held together by a spiral hinge *h* which, as will hereafter be seen, is utilized to hold the notebook between the covers 1, 1'. The covers 1, 1' are held together by a flexible back 2 in any manner known to the bookbinders' art. A pair of hooks 3, 3 are riveted to the back 2 in opposing relation and

near the margin thereof for supporting the notebook N by engagement with the open ends of the spiral hinge *h*, as shown in Figs. 1 and 4. The spiral hinge *h* is compressible longitudinally so that it may easily be compressed within the 5 compass of the space between the hooks 3, 3, properly positioned between the hooks, and allowed to expand on the hooks.

In order to support the covers 1, 1' in erected position, as shown in Fig. 5, a ribbon or flexible 10 band 4 is secured to the covers parallel to the side edges thereof and in close proximity to one of said edges, said ribbon being of a length so that when the covers are in open position 180° apart, the ribbon will be stretched from one cover 15 to the other across the back 2.

Preferably the ends 5, 5' of the ribbon are inserted through slots 6, 6' in the covers 1, 1' and secured by suitable adhesive to the inner surfaces of said covers. Facing sheets 7, 7', which 20 are glued over the inner surfaces of the covers 1, 1', cover the ends 5, 5' of the ribbon 4. In Fig. 6, the facing sheets 7, 7' are shown broken away from the covers 1, 1' to expose the ends 5, 5' of the ribbon 4. 25

The cover 1' is provided with a notch 8 in its edge 9, said notch being in alignment with the ribbon 4 and being adapted to have the ribbon inserted into it, as shown in Figs. 4 and 5, in order to hold the covers in erected position to 30 serve as a holder for the notebook N. Obviously, the length of the ribbon 4 is such that that part of the ribbon between the covers, when the ribbon is inserted in the notch 8, will maintain the spacing of the covers 1, 1' at an angle that will 35 be most convenient for the stenographer in reading his notes.

Having described my invention, I claim:

A notebook holder comprising a pair of hinged 40 covers, securing means adjacent to the hinge line of the covers for engagement with a notebook, a ribbon having its ends fixedly secured to the covers and arranged taut on the outside thereof when the covers are folded together, and a notch in one cover to receive said ribbon for 45 taking up the slack in the ribbon to maintain the covers in erected position.

JOHN H. BECKER.
